[57] CLAIM

The ornamental design for a filled pastry or the like, as shown.

DESCRIPTION

FIG. 1 is a perspective view of a filled pastry or the like showing my new design;

FIG. 2 is a top plan view thereof;

FIG. 3 is a side elevational view thereof, the undisclosed sides being substantially the same;

FIG. 4 is a bottom plan view thereof; and

FIG. 5 is a sectional view taken along line 5—5 of FIG.
2.

FIG. 1.

FIG. 2.

FIG. 5.

FIG. 3.

FIG. 4.
